DISINFECTOR

Roy A. Myers, St. Paul, Minn.

Application February 27, 1939, Serial No. 258,764

9 Claims. (Cl. 299—22)

My present invention relates to disinfectors intended for general use, but especially well adapted for use in dripping an antiseptic oil into a urinal or a closet bowl.

The object of this invention is to provide a disinfector that is relatively simple, highly efficient in operation, rugged in construction and relatively tamper-proof. The invention further provides a disinfector that also acts as a deodorizer.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a front elevation of the improved disinfector;

Fig. 2 is a view partly in side elevation and partly in section taken on the line 2—2 of Fig. 1;

Fig. 3 is a plan view of the improved disinfector;

Fig. 4 is a view partly in elevation and partly in section taken on the irregular line 4—4 of Fig. 2;

Fig. 5 is a rear elevation of the improved disinfector;

Fig. 6 is a view partly in elevation and partly in section taken on the line 6—6 of Fig. 2;

Fig. 7 is a fragmentary detail view principally in section taken on the line 7—7 of Fig. 6;

Fig. 8 is a fragmentary detail view principally in section taken on the line 8—8 of Fig. 5;

Fig. 9 is a fragmentary detail view principally in section taken on the line 9—9 of Fig. 4; and

Fig. 10 is a fragmentary detail view principally in section showing the reservoir by means of full lines, as the same is placed in the bowl before the valve is opened, and also showing the reservoir, by means of broken lines, supported on the bottom of the bowl with the valve open.

The improved disinfector includes a bowl 11 having a removable lid 12 and a wall bracket 13. Said lid 12 is in the form of a hood and the shape thereof is substantially like that of the bowl 11 except that it is inverted and has an open back and a forwardly and downwardly sloping top.

The wall bracket 13, as shown, is a flat plate, the lower end portion of which, snugly fits into a recess 14 therefore in the back of the bowl 11 and the upper portion of said wall bracket affords a closure for the open back of the lid 12. To

detachably secure the bowl 11 to the wall bracket 13, I provide a pair of hooks 15 that are cast with said bracket on the face thereof and separably interlock with the rim portion of the bowl 11. To further detachably secure the bowl 11 to the wall bracket 13 I also provide a pair of screws 16 that extend through holes in the wall bracket 13 and have threaded engagement with lugs 17 cast in the lower rear corners of the bowl 11. The snug fit of the wall bracket 13 in the recess 14, together with the hooks 15 and the screws 16, rigidly secure the bowl 11 to the wall bracket 13.

Cast with the wall bracket 13, on the face thereof above the bowl 11, is a pair of laterally spaced 15 upright reinforcing ribs 18.

The lid 12 loosely rests on the rim of the bowl 11 and its top and side members cap the respective edges of the wall bracket 13 and thereby hold the lid 12, at its back, positioned on the bowl 11 against relative lateral shifting movement.

To further hold the lid 12 on the bowl 11 a dowel pin 19 is anchored at its lower end portion in the rim of said bowl, at the front thereof, and extends, with a working fit, into a seat 20 therefore in the lower edge portion of the lid 12. This dowel pin 19 together with the capping of the lid 12 with the wall bracket 13 holds the lid 12 on the bowl 11 against horizontal shifting movement in all directions.

A hidden lock is provided for releasably securing the lid 12 to the wall bracket 13 and includes a headed lockbolt 21, on said bracket, and a lock seat 22 for said bolt on the lid 12. The lock bolt 21 is mounted for endwise sliding movement in axially aligned holes in a pair of laterally spaced lugs 23. These lugs 23 are cast with the wall bracket 13 on its inner face and at the top thereof. The lock seat 22 is in the form of a bore which extends transversely through a reinforcing rib 24 in axial alignment with the lock bolt 21. This rib 24 is cast with the lid 12, on its under side and extends from the front to the rear of said lid and into a notch 25 in the upper edge portion of the wall bracket 13. A transverse pin 26, in the lock bolt 21, between the lugs 23, limits, by its engagement with said lugs, the endwise sliding movement of the lock bolt 21.

In the upper rear edge portion of the lid 12 are notch-like apertures 27 through, certain of which, an instrument may be inserted to engage the head of the lock bolt 21 and withdraw the same from its lock seat 22 to release the lid 12 from the wall 55.

bracket 13. This instrument may also be used to force the lock bolt 21 into its seat 22 and thereby lock the lid 12 to the wall bracket 13.

The wall bracket 13 may be secured to an upright support, such as a wall, by a bolt or any other anchoring device or devices such as screws, not shown. To receive such securing means, a relatively large hole 28 is formed in the wall bracket 13, substantially at the center thereof above the bowl 11, and a plurality of screw holes 29 are also formed in said bracket and spaced about the hole 28, see Fig. 4.

Formed as integral parts of the lid 12 and the bowl 11, is a guard reinforcing rib 30 which, in cross-section, is in the form of an inverted V the sharp edge of which projects outwardly from the lid 12 and the bowl 11. This rib 30 extends from the rear edge of the lid 12, at the top thereof, to the rear edge of the bowl 11 at the bottom thereof.

Upper, intermediate and lower rows of vertically elongated apertures 31, are formed in the lid 12 and the apertures in each row extend along the front and sides of the lid 12.

Within the bowl 11 are two vacuum siphon systems, but only one of which is in use at a given time. One of these systems is at the back of the bowl 11 and the other of which is at the front thereof. Each system, when in use, includes a siphon wick 32 held in the shape of a siphon tube. The wick 32 when used in connection with the back system has its short leg held in an upright, channel-shaped member 33 and its long leg is held in an upright tube 34.

When the wick 31 is used in connection with the front system its short leg is held in an upright channel-shaped member 35 and its long leg is held in an upright tube 36. The members 33 and 35 have on their sides, out turned flanges 37 and 38 respectively, and which flanges are slidably mounted in ways 39 and 40 respectively. These ways 39 and 40 are cast integral with the back and front members of the bowl 11, respectively, and frictionally hold the channel members 33 and 35 with their lower ends spaced above the bottom of the bowl 11 for the movement of the liquid in the bowl 11 to the respective legs of the wick 32. It will be noted that the open sides of the channel members 33 and 35 are turned toward the respective members of the bowl 11 and are closed thereby.

The tubes 34 and 36 are held in upright positions by having their lower end portions fitted into sockets in lugs 41 and 42 respectively, cast integral with the bottom and the respective side members of the bowl 11. An upright nipple 43 is mounted in the lug 41 and leads from the lower end of the tube 34 through the bottom of the bowl 11. Said bowl 11 at its under side, is recessed, as indicated at 44, to afford clearance for a tube 45 fitted onto the nipple 43 and only fragmentarily shown by means of broken lines, see Fig. 8.

A second nipple 46 is fitted in the lug 42 and leads from the lower end of the tube 36 through the bottom of the bowl 11, see Fig. 7.

Within the bowl 11 is a body of antiseptic dripping oil X supplied thereto from a reservoir 47 in the form of a closed upright can. This reservoir 47 has on its lower end a depending neck comprising a fixed tube 48 on which is telescoped a tube extension 49 having a flaring mouth 50. This mouth 50 loosely rests on the bottom of the bowl 11 and supports the reservoir 47 within said bowl and its lid 12.

The tube extension 49 has formed therein, a deep notch 51 which extends from the upper edge of said extension to an aperture 52 in said extension at the junction of the mouth 50 therewith. This notch 51 and the aperture 52 afford a passageway for the flow of an antiseptic dripping oil Y from the reservoir 47 into the bowl 11. The tube extension 49 frictionally holds the tube 48 where telescoped therein. By contracting the tube extension 49, at the notch 51, its frictional contact within the tube 48 may be increased at will. To fill the reservoir 47 with an antiseptic dripping oil, it is turned into a position in which the tube 48 and its extension 49 are at the top thereof.

At the time the reservoir 47 is placed in the bowl 11 the same is inverted, and to hold the liquid Y therein I provide a valve 53, which, when closed, is seated on the inner end of the tube 48, see Fig. 10. This valve 53 is provided with a stem 54 which extends axially outwardly through the tube 48 and its extension 49. The outer end portion of the valve stem 54 is bent to form a ring 55, which, when the valve 53 is closed, extends partially outwardly of the mouth 50. It will be noted that the external diameter of the ring 55 is somewhat larger than the internal diameter of the tube 48 and acts as a stop to prevent the valve 53 from dropping into the reservoir 47, when said reservoir is turned into a filling position.

Formed in the tube 48, close to the respective end of the reservoir 47 is a hole 56, for a purpose that will presently appear.

During the placing of the reservoir 47 in the bowl 11, the ring 55 engages the bottom of said bowl and opens the valve 53, by stopping further movement thereof, as the reservoir 47 is lowered to position the mouth 50 on the bottom of the bowl 11. When the valve 53 is open the liquid Y will flow from the reservoir 47 through the notch 51, aperture 52 and the hole 56 into the bowl 11 until the level of the liquid X in said bowl is just above the hole 56. This level of the liquid X is maintained until the liquid Y in the reservoir 47 drops below a level in which the hole 56 is uncovered and thereby breaks the partial vacuum in the reservoir 47 and stops further siphoning of the liquid X from the bowl 11.

When the improved disinfecter is used in connection with a closet bowl the same is attached to a suitable support thereabove and the tube 47 has its delivery end extended into said bowl to drip the liquid therein. In this use of the disinfecter the wick 32 will be placed as shown in Fig. 4.

If the improved disinfecter is to be used in connection with a urinal, the wick 32 will be placed as shown in Fig. 6, and the disinfecter mounted in a position in which the liquid X will drip from the nipple 46 directly into the urinal.

At the same time, the improved device is used as a disinfecter, the same may also be used as a deodorizer and in which case a tubular wick 57 is telescoped over the reservoir 47 with its lower end portion extending into the liquid X, see Fig. 2. Fumes from the liquid X held by the wick 57 will escape from the disinfecter through the apertures 31 and enter the room in which the disinfecter is placed.

To assemble the several parts of the improved disinfecter the lower end portion of the wall bracket 13 is placed in the recess 14 and slid downwardly therein to interlock the hooks 15 with the back rim of the bowl 11 and thereafter the screws 16 are inserted through the holes 75

therefor in said bracket and screwed into the lugs 17. Next the wall bracket 13 is fastened to a wall or other support by means of a bolt or other anchoring device inserted through the hole 28 or by screws inserted through the holes 29.

Before the lid 12 is secured over the bowl 11 the reservoir 47 is filled with an antiseptic dripping oil and then placed in the bowl 11 as hereinafore described. If the antiseptic oil is to be dripped from the nipple 43 the wick 32 will be placed, as shown by full lines in Figs. 2, 4, and 8. Or if the antiseptic oil is to be dripped from the nipple 46 the wick 32 will be placed as shown by broken lines in Figs. 2, 6, and 7.

After the reservoir 47 is in place in the bowl 11, the lid 12 is placed on said bowl with the dowel pin 19 in its seat 20 and the rear edge portion of the lid capping the wall bracket 13. Next the lock bolt 21 is moved endwise into the lock seat 22 to lock the lid 12 to the wall bracket 13.

When the wick 31 has become saturated with the antiseptic oil the siphoning action will start and said wick will continue to drip oil until the partial vacuum in the reservoir 47 is broken by the lowering of the liquid level into a position in which it uncovers the hole 56.

It is evident that when the wall bracket 13 is secured to a support, the bowl 11 cannot be removed therefrom for the reason that the screws 16 are covered by said bracket and can not be reached. Neither can the wall bracket 13 be removed from its support for the reason that its fastening device is covered by the lid 12 which is locked to the wall bracket 13.

Unless a person is familiar with the location and operation of the hidden lock, which secures the lid 12 to the wall bracket 13, he cannot gain access to the interior of the device.

It is well known that vandals often try to break, mutilate or otherwise damage disinfectors in the toilets of public buildings, schools and the like. This damage is often done by striking a disinfecter with a bar or club or by striking the same with the fist. The primary purpose of the reinforcing rib 30 is to protect the disinfecter from being damaged by a blow thereon. Furthermore, the lid 12 is securely held on the bowl 11 and cannot be twisted or pried therefrom.

The amount of liquid dripped from the disinfecter may be varied at will by moving the tube 48 axially into the tube extension 49 to vary the height of the hole 56 above the bottom of the bowl 11 or in other words to vary the level of the liquid in the bowl 11.

The drawings illustrate a commercial form of the invention, but it will be understood that the same is capable of certain modifications as to details of construction, arrangement of parts, and combination of parts within the scope of the invention herein disclosed.

What I claim is:

1. A device of the kind described comprising a bowl having a recessed back, a hood-like lid for the bowl having an open back, a wall plate the lower end portion of which is fitted into said recess, the upper end portion of said plate affording a closure for the open back of the lid, said plate having a hook-like member arranged to be interlocked with the rim portion of the bowl by endwise sliding movement of the wall plate in the recess, and means operable from the back of the

wall plate for detachably securing the bowl thereto.

2. A device of the kind described comprising a bowl, a hood-like lid for the bowl having an open back and resting on the upper edge of the bowl and forming a continuation of the front and sides thereof, a wall plate to which said bowl is attached, said plate affording a closure for the open back of the lid, and a hidden lock in the lid releasably securing said lid to the wall plate, said lid having an aperture through which an instrument may be inserted to operate the lock.

3. A device of the kind described comprising a bowl, a hood-like lid for the bowl having an open back and resting on the upper edge of the bowl and forming a continuation of the front and sides thereof, and a wall plate to which the bowl is attached, said plate affording a closure for the open back of the lid, said plate having an aperture above the bowl through which a fastening device may be inserted to secure the wall plate to a support.

4. The structure defined in claim 2 in which the lock includes a slidable bolt.

5. The structure defined in claim 2 which further includes an internal reinforcing rib on the lid, and in which structure the lock includes a bolt slidably mounted in a pair of lugs on the wall plate and arranged to be moved endwise into or out of a lock seat in said rib.

6. A device of the kind described comprising a bowl, a hood-like lid resting on the rim of the bowl and having an open back, a wall plate to which the bowl is attached, said plate affording a closure for the open back of the lid, said lid at its rear edge portion capping the respective edge portions of the wall plate, and a dowel pin releasably connecting the lid to the bowl at the front thereof.

7. A device of the kind described comprising a bowl, a hood-like lid for the bowl, a wall plate to which the bowl is secured, and means for securing the lid relative to the bowl, said bowl and lid having an external outstanding sectional guard rib extending from the top of the lid at the back thereof, and forwardly and downwardly to the bottom of the bowl at the front thereof, said guard rib being V-shaped in cross-section with its sharp edge outermost.

8. A device of the kind described comprising a bowl, a closed reservoir having on its bottom a depending tube, a tube extension telescoped onto the tube with its lower end resting on the bottom of the bowl and supporting the reservoir therefrom, said tube extension having a liquid escape passageway, said tube having an aperture above the passageway for breaking the partial vacuum in the reservoir when the liquid level in the reservoir has moved therebelow, and a siphoning system for dripping liquid from the bowl, said tube being adjustable on the extension to vary the height of the aperture therein above the bottom of the bowl.

9. In a device of the kind described comprising a bowl, means for supplying liquid to the bowl, a siphoning system for dripping liquid from the bowl, said system including a wick and means for holding the wick in the shape of a siphoning tube, including a tube for holding one leg of the wick and a channel member for holding the other leg of the wick, said channel member being slidably mounted in ways on the bowl.

ROY A. MYERS.
